(57) **CLAIM**

I claim the ornamental design for pants, as shown and described.

DESCRIPTION

FIG. 1 is a front view of pants according to the present invention.

FIG. 2 is a rear view of the pants of FIG. 1.

FIG. 3 is a left side view of the pants of FIG. 1; and,

FIG. 4 is a right side view of the pants of FIG. 1.

The broken lines, shown throughout the views, represent stitching, which forms part of the claimed design.
